atty.

Patented Apr. 7, 1925.

UNITED STATES PATENT OFFICE.

LEON REVERA PAUL, OF CHICAGO, ILLINOIS.

BATHTUB.

Application filed March 7, 1924. Serial No. 697,550.

To all whom it may concern:

Be it known that I, LEON R. PAUL, a citizen of the United States, residing at Chicago, in the county of Cook and State of Illinois, have invented new and useful Improvements in Bathtubs, of which the following is a specification.

The present invention has relation to bathing apparatus and refers particularly to a combination tub and shower bath.

Some patents have issued on such combinations, but the structures of these patents have not been found commercially successful, for the reason that the person bathing in one of these devices must rise from a reclining position, pass to the other end of the bath-tub, turn around and then seat himself, in order to make use of the spraying devices of such tubs.

The object of my invention is the provision of a bathing apparatus in which the bather, if he so chooses may enjoy his tub bath, as usual, and then without rising or turning, but by simply opening a faucet conveniently located, may turn on sprays in order to rinse off the soapy water of the tub bath.

To this end my invention consists in the combinations hereinafter fully described and claimed and drawings are hereto attached, in which structures embodying the invention are illustrated.

In the drawings:

Fig. 1 is a cross sectional elevation substantially through the center of a structure embodying the invention.

Fig. 2 is a similar view illustrating means of converting an ordinary bath tub into the combination device of my invention, and

Fig. 3 shows the bath-tub attachment removed from its position indicated in Fig. 2.

The structure of Fig. 1 is a bath-tub of the most modern type comprising a bowl 1 completely surrounded by a flange 2. This is considered the best practice where the tub is placed away from the bath room walls. In small bath rooms, of the apartment type, the tub is usually fitted in between three walls, in which case the flange 2 ordinarily is omitted on the three sides where it cannot be seen. The usual supply pipes 3 lead hot and cold waters to a faucet 4, and a drain 5 is set in the bottom of the bowl, all as found in practice.

At the head end it is noticed that the

bowl and flange extend upward to form a vaulted hood 6, the height of which should be so calculated that the head of a person rising from a sitting position will clear the upper front edge 7 of this hood. The front edge 7 of the hood is tubular and this tubular portion may extend downward to the top edge 8 of the bath-tub proper, if so desired. Two or more rows of apertures 9, 10 are cut into this tubular edge to form a spray, and the angular direction of these apertures may be calculated so as to play fine streams of water practically over the entire surface of the bowl, care being taken, of course, that the spray is not directed too close to or outside the top edge 8 of the tub.

Substantially in the center of the dome may be mounted an ordinary shower spray 11, through which a stream of water may be directed over the head and shoulders of a person sitting or reclining in the tub.

From the foregoing it should be clear to anyone accustomed to the use of a modern bath room equipment, that he can take his tub bath and shower in the structure of my invention without moving, except as required in order to lift the drain plug out of the drain; an advantage not attainable in any other bath-tub, so far as I am aware.

The proper method of water connections may well be governed by regulations or ordinances of the places where the structure is to be installed for use, and the following description is merely given for the purpose of indicating a complete operative device. Into the supply pipes 3 may be cut T's 12 from which pipes 13, 14 and 15 lead to a pipe 16, which in turn carries water to the edge sprays 9, 10 and the shower spray 11. At any suitable point in the pipe line are placed a pair of faucets 17, 18, which control the flow of water to the sprays. These faucets should be so placed that they may be conveniently operated by the bather from either a sitting or reclining position, and the operating handles should preferably be set close to or sunk into the wall of the structure in order not to catch the arm or shoulder of the bather. There may, of course, be provided additional valves 19, 20, capable of cutting off the flow either to the edge sprays or the head shower, if such should be desired, and in case such control valves are employed they should be conveniently placed.

A bath-tub 30, of the old and universally used type is here shown fitted with supply pipes 31, faucet 32 and drain 33. The vaulted portion is in this case a separate 5 cast or sheet metal hood 34 provided with a tubular front edge 35, in which rows of spray perforations 36 are placed, as hereinbefore described. A shower spray 37 is also placed substantially in the middle of 10 the dome, as in Fig. 1.

The vaulted portion may be made with the inner hood 34, as indicated, and this hood may be surrounded by a shell 38, partly 15 in order to cover the necessary pipe connections and mostly for the sake of appearances. But it is important to note that the hood should be made with a curved flange, or apron 39 of a size to extend inwardly over the curved top edge of the 20 bath-tub, in order that the water from above may drain into the bath-tub, and also so that the attached hood may set firmly 25 on the tub. The wall of the hood may then set back from this apron, as indicated in the drawing, in order to afford more elbow room.

The pipe connections may remain substantially as described in connection with 30 Fig. 1, and the device may be delivered with all necessary pipes and valves 42, 43, in place, so that it only will be necessary to cut a pair of T's 40 into the supply 35 pipes 31. Even this may be avoided, and a rubber hose, such as commonly used in connection with detachable bath sprays, may 40 be pushed on the nipple 41 of the faucet 32. In this case the valves 42, 43 should be omitted and a nipple placed on the pipe 44, upon which to attach the other end of 45 said hose. And if this nipple is caused to project inward through the wall of the hood it is readily seen that the rubber hose will be entirely within the tub, and that no water will be spilled outside.

Whether a one piece structure, such as shown in Fig. 1, or an attachment to an old bath-tub, or whether fixed pipe connections or rubber tube connections be considered, it is clear that the importance of

my invention resides in the fact that a 50 curtainless structure is obtained in which a person may enjoy both tub and shower bath without changing position.

Reference was made above to the angular direction of the spray perforations 9, 55 10, which must be so that the water will not fly outside the tub. A better way, although of course also a little more expensive, is to form the edge of the tub more 60 nearly into a triangular cross sectional 60 shape, substantially as indicated in Fig. 1, and to place the apertures in the inner side of this triangle. If then the edge 7, 8 is 65 formed into the shape of an inwardly projecting lip as shown, it is clearly seen that 70 this lip will deflect any water tending to project beyond the tub. The apertures 9 and 10 should be close to the corners of the triangle so that water remaining after bathing may drain out.

I claim:

1. As an attachment to a bath tub, an arched hood provided at the bottom with a curved flange fitting over the roll-edge 75 of the tub and made along its arched front edge with a tubular rim having rows of orifices inwardly directed, the hood comprising between the flange and the said rim an outer and an inner wall, there being in said inner wall a recess, water connections leading into the space between said walls, and control valves in said connections having handles seated in said recess.

2. As an attachment to a bath tub, an open-front hood seatable on said tub and 85 made with a tubular rim along its front edge, said rim provided with inwardly directed orifices, a shower spray in the top of said hood, the hood having an outer arched wall rearwardly extending, whereby 90 an arched chamber is provided, open at the back, and water connections leading into said rim and shower spray, said connections seated in said chamber and operable within the hood.

In testimony whereof I have hereunto affixed my signature.

LEON REVERA PAUL.
